Claims priority, application Great Britain Jan. 7, 1958

9 Claims. (Cl. 34—1)

The present invention relates to drying of wet structures, including parts of the human body as well as durable consumer goods, and comprises the evaporation of absorbed vapours or liquids and the setting or curing of paint and synthetic resin compositions. In particular it relates to drying by the aid of heat, of relatively thin layers in which it is of importance that the temperature should not exceed a safe limit at any point. An object of the invention is to accomplish such heating electrically at a high rate, in an economic and convenient manner. Other objects will become apparent as the description proceeds.

The invention provides a method of drying a durable structure at rest which includes a layer having absorbed therein a fluid and requiring to be heated to dry the layer, which comprises fixing a heating film to said structure in heat conductive connection with said layer over an area corresponding to substantially the whole area of said layer, a major part of the area of the film being occupied by an electrically conductive surface pattern substantially uniformly distributed over it, and passing through the surface pattern an electric current of sufficient intensity to raise its temperature but only to a value below that at which the combination of the pattern and the structure would be damaged during the time of application of the heat.

It is to be understood that the term "durable structure at rest" means that the structure does not consist of consumable goods or loose bulk material such as grain or chemicals and that movement as such has no part in the drying process. The drying of such goods and materials is a different problem from that with which the present invention is concerned.

The invention also provides a combination comprising a durable structure which includes at least a layer having absorbed therein a fluid and requiring to be heated to dry the layer, and a heating film fixed to said structure so that the film and structure are relatively at rest, said film having a heat conductive connection with said layer over an area corresponding to substantially the whole area of said layer, a major part of the area of the film being occupied by an electrically conductive surface pattern having at least two terminal zones and being substantially uniformly distributed over the area with substantially constant resistance per unit area and aggregating in a small total resistance of the whole pattern between terminal zones so that the voltage drop produced by a relatively heavy current across the said terminal zones is of such value that the watt loss in the heating film including the terminal zones is at no point capable of raising its temperature to a value at which the combination of the film and the structure would be damaged during the time of connection to the supply.

It will be clear that the heating film being a very thin material, is of small mass and therefore of very low heat inertia. It will also be clear that such a thin material is very flexible.

By the expression "relatively heavy current" is meant a current in the range of amperes, as distinct from milli-amperes or kilo-amperes, and by the expression "small total resistance" is meant a resistance in the range of ohms as distinct from milli-ohms or kilo-ohms. Desirably the voltage drop is of such low value that it is not dangerous to human contact, that is usually below 50 volts.

2

It will be clear that the development of heat must not be greater per unit area of the terminal zones than elsewhere and this is preferably achieved by making the cross-sectional area of each terminal zone not less than the aggregate cross-sectional area of the pattern corresponding to the total resistance. In general there will usually be a number of paths in parallel between the two terminal zones and the cross-sectional area of each terminal zone will then be not less than the total cross-sectional areas of the several parallel paths. An alternative way of keeping down the development of heat at the terminal zones would be to add metal of higher conductivity to them as by clamping or plating.

Since the area occupied by the film substantially corresponds to the area of the surface to be treated and since the major part of the area is occupied by the conductive pattern substantially uniformly distributed over it, maximum use of the area available is made while anything in the nature of hot spots is avoided so that a maximum rate of heat dissipation for the particular conditions can be achieved. Where local conditions made it desirable or necessary the pattern or the scheme of connections can be varied in different parts to achieve a number of zones each uniform but providing for different rates of heat dissipation. In some cases for instance the intensity of heating may need to be less in the centre as compared with the margins but uniformity is maintained within these zones.

It is to be understood that the heating film is only connected to the supply temporarily that is to say when the actual heating is performed. Purely resistive heating by connecting the pattern directly to the supply is envisaged. The invention is not concerned with methods or apparatus in which the energy is transferred to the pattern inductively or capacitively.

The invention will be further described with reference to the accompanying diagrammatic drawings in which:

FIGURE 1 is a plan view of one form of heating film used in the invention with some parts broken away,

FIGURE 2 is a plan view of an alternative form,

FIGURE 3 is a section which applies equally to FIGURE 1 or 2,

FIGURE 4 illustrates the application of the invention to the drying of paint,

FIGURE 5 illustrates the application of the invention to the curing of plastics,

FIGURES 6 and 7 illustrate developments of the conductive pattern of the films of FIGURES 1 and 2 respectively,

FIGURE 8 is a detail section illustrating a further development,

FIGURE 9 illustrates the application of the invention to an absorber type refrigerator,

FIGURE 10 illustrates the application of the invention to a hair curler,

FIGURE 11 illustrates the application of the invention to a towel,

FIGURE 12 illustrates the application of the invention to the ironing of garments.

In the form shown in FIGURE 1 the conductive pattern is a thin flexible metallic foil 11 having a series of slots 12 which leave a plurality of parallel meandering paths extending from terminal zones 13 constituted by the areas along the sides of the pattern. If the width of the arms of the pattern is kept constant each meandering path will present the same overall resistance and the same resistance per unit length and if a voltage is maintained from one terminal zone 13 to the other between the terminal zones the same current will flow in each path whatever the length of the film. There will thus be a substantially constant dissipation of heat per unit area

over the whole film. The film shown in FIGURE 1 can moreover be cut into narrower pieces since any portion between adjacent lines of slots can serve as the terminal zone. It will be clear that however many meander paths are left between terminal zones the cross sectional area of the terminal zones is greater than that of the arms of the meander pattern.

In FIGURE 2 the pattern is similar to that in FIGURE 1 but the slots 14 extend across the foil 15 and the terminal zones 16 are at the ends. Such a film can be cut into pieces by transverse cuts as any portion between successive lines of slots can serve as terminal zones.

In some cases the film need not consist of anything more than the metal pattern, but if necessary or desired there may be an insulating film indicated at 17 on one side of the foil 11 or 15 and there may be another indicated at 18 on the other side. Such insulating film may be of plastic or paper for example.

In general the structure in connection with which the film is used will be a multi-layer structure of which one layer is the layer containing the absorbed fluid to be heated, and the structure at the time the current is switched on will be at room temperature. Where the heating operation causes vapours to be driven off and these vapours have to escape on the same side as that to which the heating film is applied the heating film will have small passages through and it will be made porous or perforated as indicated at 19 FIGURES 1 and 2 to allow for the passage of vapour without harm to it or the structure on which the film is used. Such small passages may be useful in other cases. In many cases the heating film itself will be of cheap construction so that it can be thrown away after once using but the invention also includes cases in which the film is retained for repeated use whether in connection with the same layer or by transfer from one layer to another. Often the heating film is provided with an adhesive coating for example a self-adhesive pressure sensitive material to permit easy fixing to the structure.

It is desirable to ensure that if the film is to be used repeatedly but on different layers it can be transferred from one to another without suffering damage because if the pattern is damaged and is still conductive, the distribution of resistance will be affected and there will be a risk of hot spots. If on the other hand it is made of cheap construction so that it can be thrown away it should desirably be made so flimsy that it is practically impossible to avoid destroying it in removing it after use.

In all cases where the pattern can be contacted by a human operator it is so designed that the necessary heating effect can be obtained by a supply of electric current at a low voltage that is to say at a voltage which does not constitute a risk to the operator if he comes into accidental contact with the pattern. Such voltages are usually below 50 and often well below 50 say 12 volts, 6 volts or even lower. Such voltages also make it permissible in many cases e.g. where the layer to be dried is not conductive, to allow the layer to touch the bare pattern. These voltages have the advantage of simplifying the construction of the film and its use, since the insulating problems presented by high voltages do not arise. It also makes it possible to use the heating films for such purposes as hair driers and curlers, and for other domestic purposes such as the drying of foot-wear, clothing, towels and the like or other textile fabrics.

Other fields of use are in connection with the drying, the drying and curing, or the drying, curing and heating of paint and similar materials, and of plastic structures and fabrics.

Thus one major field of application of the heating film is its incorporation in structures which are painted. The incorporation may be temporary or permanent. It is proposed for instance to stick a heating film 21 FIGURE 4 on the underside of sheet metal work indicated at 22 before it is painted as at 23. Since the workpiece is metallic there must be an insulating layer between the actual

5 pattern and the workpiece as at 24, but this may be part of the heating film. No insulating layer is shown on the other side of the film 21 but it can be provided if desired. The paint is now dried by supplying current to the heating film instead of by the present methods of stoving the panels or applying heat to them by other means. Since metal is a good conductor, the heat from the film 21 reaches the paint 23 without a steep temperature gradient, or in other words the paint 23 is brought to a temperature but little below that reached by the film 21 and due to the lay out of the conductor in the film 21 the heating is substantially uniform over the whole surface. This not only gives an improvement in drying or curing conventional paints but it often permits the substitution 10 of stoving enamels for air drying paints. Another major field of application is the incorporation of the film in plastic structures and fabrics such as low pressure laminates, articles made with potting resins, plastic castings and larger scale mouldings requiring heat for quick setting. FIGURE 5 shows by way of example an embodiment 15 with the heating film 25 (which here can be a bare foil pattern) between two layers 26 of fibre-glass and uncured resin i.e. within the thickness of a plastic structure. The slow drying and curing process of these plastic fabrics is at present hindering the use of these in many industries requiring speedy output from the moulds, presses or jigs for their formation. Thus the production 20 of glass-fibre structures by the socalled wet-lay process is restricted for mass production applications by the practical difficulty of and equipment required for accelerating the heat drying and curing of the structure. The incorporation of the heating film in such structures enables them to be dried and cured quickly and the moulds to be liberated more frequently with consequent saving in floor 25 space and equipment. Heating films incorporated in plastics preferably have small passages (i.e. small holes or pores) through which the fluid resin can flow.

It should be mentioned that the term plastic is used 30 herein to indicate not only materials which when cured are substantially rigid but also materials which are elastomeric, such as natural and synthetic rubber, and polyvinyl chloride.

Where a paint layer, a plastic or fabric is part of an 35 article which subsequently needs to be heated during use or where heating provision for repairs is desired, the film used for the initial operation of drying, curing, etc. may remain in situ and serve subsequently as a heater in the use or repair of the article. In that case the conductive pattern will be laid out so that it can conveniently serve 40 both purposes. Thus it may be operated at different voltages in its original and subsequent uses or it may be arranged so that it can be reconnected to give a different heat output when supplied with current at the same voltage.

50 Examples of articles in which the same heating film may be used in the original production of the article and in its subsequent service are radiating panels, ironing boards, door mats, vessels such as tanks, beakers, baths and sinks, and pipes, pots, pans, dishes and draining boards.

55 Yet another field of use of the heating film is in connection with refrigerators of the absorption type.

As above explained, the heating film used in the invention 60 is essentially a thin flexible pattern, preferably of metallic foil, and can be made by several of the now well known printed circuit techniques. Improved and preferable methods for making these films have been described in my applications Serial Nos. 747,315 and 747,314, filed July 8, 1958, and particularly Serial No. 783,633, filed November 10, 1958. The last application describes a heating pattern which is especially suitable for many applications of the present invention when made with aluminium foil coated on both sides. The use of a very low voltage permits the use of stronger foils, and

overall, additional plastic film support is sometimes not necessary at all.

As also above explained, the pattern will generally be a meander pattern as shown in FIGURES 1 and 2 in elementary form and as described in these prior applications. Preferably the pattern is such that numerous meander patterns are provided in parallel each pattern covering only a small area of the same convenient module i.e. unit size. Then a standard film can be produced in rolls of great width and length and can be cut to required size and shapes when the quantity of articles to which it is to be applied is not great enough to warrant the production of a pattern specially for the job. This enables the invention to be applied readily to repair and maintenance work and enables such materials as stoving enamels to be used for this type of work where their use might be otherwise very inconvenient or quite impracticable because the painted surface is in a location or on an article which it would be inconvenient or impossible to transfer to an oven for stoving. The film may be provided with a self-adhesive coating enabling it to be readily applied and stripped after use and can easily be made cheap enough to be dispensible. However with a suitable adhesive it can be stripped without damage and can be re-used, if necessary after a fresh adhesive has been applied to the film or workpiece.

Even where stoving would be possible the present invention enables ovens or hot presses to be dispensed with and while the film may be dispensible, in other cases it may be left permanently in position on the underside of articles having a thin enough wall to make the heat transfer effective, or even between the surface of the article and the layer of paint. In this field the invention may be applied for example to shaped parts of automobile body work, sheet metal parts of domestic equipment such as washing machines, and metalwork in buildings such as pipes, doors and windows and can be used for the original paint drying, while thereafter damage to the paint-work can be repaired even with a stoving enamel. In all these cases, if the film is made with a crimped foil pattern as in my said application Serial No. 783,633 the film can readily be applied to intrinsically curved surfaces.

If the pattern contains numerous repeats with separate terminal zones brought out or accessible at adequate intervals heating can readily be confined to a particular area in the case of local repairs or other cases where this is desirable. Thus in FIGURE 6 which shows only the conductive pattern on the lines of FIGURE 1, slots 27 subdivide the marginal terminal zone into separate zones for each double meander path while in FIGURE 3 which shows only the conductive pattern on the lines of FIGURE 2, slots 28 sub-divide the transverse terminal zone into separate zones for each double meander path. It usually suffices however to provide such slots at less frequent intervals.

As applied to plastic structures and fabrics the film can be applied to the surface or within the thickness of the material and in the latter form it is preferably perforated. It is particularly applicable to laminated products made from fibre-glass by the so-called wet-lay process.

In all the above cases the heat is conveyed to the layer to be heated by conduction and where consideration of strength appearance or the like do not make it objectionable it is advantageous as in FIGURE 8 to use a heat transmitting layer 31 next to the film 29 which contains heat conductive particles 32 such as graphite or aluminium or other metal powder to ensure better heat conduction in the desired direction while a heat insulating layer 33 such as glass or asbestos fibre is applied on the other side of the heating film to reduce loss of heat in this direction. Such heat insulating layers may be bound with a resin which will resist a higher temperature than that to which the film rises in operation. If necessary a thin electrical insulating layer 34 which will resist the

temperature involved may be used between the heating film and the graphite or metal filled layer. Such an insulating film will be necessary for instance where the heating film itself is a bare metallic pattern.

5 The layer 34 may be regarded as such a layer or as part of the heating film. The layer 31 may be used without the layer 33 or the layer 33 without the layer 31 with less effect than when both are used. By providing the heat conductive layer 31 a heavier loading in watts per unit area can be used without the development of excessive temperatures or hot spots.

10 In the case of an absorption refrigerator, since the method of the invention enables the heat to be applied over a very large area, the times of the alternate phases 15 of absorption of the vapour and of regeneration of the solid can be substantially shortened. In this particular application the film will be porous or perforated and is preferably made into flat bags which enclose a very thin layer of the absorbent solids and therefore presenting a 20 maximum surface of the solids both to the vapour coming from the evaporator and to the heat carried at a high rate to the solid from the large surface area of the film.

25 A suitable arrangement is shown in FIGURE 9. Between a pipe line 35 leading from the evaporator and a pipe line 36 leading to the condenser, the pipe is formed into two branches 37, 38, interlinked change-over valves being provided at 39, 41 so that at any instant one branch is connected to the evaporator and the other to the condenser. In the position shown the branch 37 is connected to the evaporator and the branch 38 to the condenser. 30 In each branch is carried a heating film bag 42, 43 confining the absorbent powder in a thin layer. The film is porous but the pores must be of such size that they do not become choked by the powder. In the position shown 35 the film 43 is being heated so driving off the absorbed vapour to the condenser while the film 42 is not supplied with current and the solids are absorbing the vapours coming from the evaporator. The supply of electricity to the two films is controlled by switches interlinked with the 40 valves 39, 41. The two-branch arrangement and the cycle of operations provides for a constant flow from the evaporator to the condenser, but by using 4, 6 or 8 branches instead of only two and arranging for the periods to overlap, the vapour flow can be made still smoother.

45 The branches are preferably very shallow metal bodies with very large surfaces which may be air or water-cooled. Cooling fins are diagrammatically indicated at 44. It will be understood that the figure shows the narrow depth and the length of the branches and that they also extend to a considerable width in the plane perpendicular to the drawing. The bags constituted by the film 42, 43 are of flat form fixed in the central plane of the branches and extend practically over the whole length and width of the branches. The heating film temperature need not 50 rise much above the temperature required for regeneration and the small mass of the film enables it to cool and heat rapidly so that changes from one phase to another both on the film and in the powder can take place very quickly. This property together with the large surface area of the film enables absorption refrigerators of larger capacity 55 to be built than at present possible.

60 The present invention can also be applied to the drying of human hair, and wearing apparel of any kind from hat to shoe. Indirectly it is also applicable to the hair and skin by use with combs, hair and other brushes, 65 towels, bandages and plasters. Such devices as hair curlers, inserts or covers for all sorts of clothing including tie-stretchers, shoe-trees and shoe-cases, may be provided with the heating film. At present such devices are mainly used as purely mechanical aids to fix, stretch or hold the hair or clothing in position or bring it into a 70 desired shape while it is air drying. Towels are only preheated in hot boxes, on towel rails or the like.

75 For these purposes a porous or perforated heating film with ample openings is used which is connected to a

source of very low voltage (battery or secondary of a transformer) to be incorporated in or attached to the above devices either permanently or as a dispensable item (to save cleaning or the expense of making them robust). A pair of insulated wires (round or flat) connects the film with the supply which is preferably of the order of 2 volts to 12 volts and may be adjustable. In many cases it is below 2 volts. One or both ends of these wires have plug-socket terminations.

The perforations in the film are preferably made after the foil pattern is laminated between two insulating films so that the holes are not clogged in the heating film production process. In many cases the perforations are not only in the gaps between the metallic areas of the film, but in the metallic areas as well, and often perforated foil is used in producing the heating films.

The film and the metallic pattern has to cover substantially the whole surface to which it is applied or under which it is fixed, and follow its outline. In hair curlers as shown for example in FIGURE 10 a plastic material reinforcing and supporting the heating film is made thick enough to form the ovoid body 45 round which the hair is wound and fixed, the connecting cable being indicated at 46, a plug connection at 47 and the supply here being exemplified by the secondary of a transformer 48. It will be understood that both the film and the plastic reinforcing material have square or similarly shaped openings giving them the same meshed form and that the reinforced film itself is rolled up and shaped to form the ovoid body 45. The same scheme is equally applicable to other well known forms of hair curler, e.g. cylindrical or flat. A hair dressing set may consist of say 2½ dozen hair curlers, each to be plugged into a socket having 30 pairs of terminals and a timed common voltage regulation or individual thermal cut-outs, followed by a timed switch-off. The timing can be so programmed that the hairdresser can undo the first curler just after he has put in the last. The timed switch-off would proceed however irrespective of the hairdresser keeping to schedule. Thermostats or heat sensing elements in the curlers are alternative safety provisions.

The provision of a heating film in a comb can be made by placing the metallic pattern in the die in which the comb is cast or moulded by injection or compression. In brushes the heating film is usually laid in the back of the brush.

Towels and bathrobes are preferably provided with an expanded, crimped and anodized foil pattern 49, FIG. 11, without overall film support, fixed to the towel by clips, plastic tape or fabric. About half the size of the towel 51 is usually sufficient for the pattern so that it is enclosed by the towel folded over it. If the foil has been coated with a tough plastic film the pattern can stand quite a number of rubs before it is discarded.

Heatable porous materials adapted for application to the human body e.g. bandages and adhesive plasters made from porous or perforated plastic film are readily provided with a crimped foil pattern by sticking a self-adhesive perforated heating film on their back, or the heating film may be embedded within the porous material.

Perforated films carrying a metal pattern can be produced as self-adhesive tapes or as shaped labels and fixed to the surface of the covers and walls of the various drying devices for clothes and shoes. For incorporation into such devices as well as for ironing purposes these films are made without adhesive backing and fixed underneath the surface of the device. For ironing the film 52, FIG. 12, serves as a heatable blanket requiring only pressure by a permeable or absorbent fabric 53, pad or net to iron the garment 54 sandwiched between two films 52, 55 compressed under the one film 52. The pressure

can be exerted by stretching the fabric 53 over a curved support 56, the film preventing creases in the garment 54 to be ironed by not transmitting the shear forces of the stretched fabric. For such purposes it has a slippery surface provided by a backing of a strong perforated metal foil or thin plastic sheet.

In some cases as well as for drying the film may also serve for heating clothing while it is being worn.

It will be clear from the various examples in the above description that the fixing of the heating film to the durable structure is effected in principle in one of two different ways. Either the film is applied e.g. stretched or pressed on or incorporated in the structure, or the structure is pressed on to the film by applying force to the structure e.g. stretching or pressing it.

I claim:

1. Structure for drying comprising metal resistance foil, an insulating layer coextensive with said foil, said foil being connected across a voltage supply at opposite ends through terminal zones, said insulating layer being perforated with a plurality of rows of bore holes, said foil having parallel rows of perforate slots with the slots of one row in staggered relation to the slots of the next succeeding row to form meandering paths for current, and the bore holes of the perforate insulating layer covering the entire area of the insulating layer so that moisture from the surfaces to be dried being transmitted through the holes and slots away from the drying surface.

2. Structure as set forth in claim 1, in which the value of the resistance is such that the voltage drop is not dangerous to human contact.

3. Structure as set forth in claim 1, in which the cross-sectional area of said terminal zones is not less than the aggregate cross-sectional area of a pattern corresponding to the total resistance.

4. Structure as set forth in claim 1, in which the insulating layer has particles of material of good heat conductivity distributed through it.

5. Structure as set forth in claim 1, in which a layer of heat insulation is provided on the face of the foil away from the drying surface.

6. Structure as set forth in claim 1, in which the insulating layer has particles of material of good conductivity distributed through it, and in which a layer of heat insulation is provided on the surface of the foil away from the drying surface.

7. Structure as set forth in claim 1, in which the structure is a porous material adapted for application to the human body.

8. Structure as set forth in claim 1, in which a coating is provided of adhesive fixing said foil to said layer.

9. Structure as set forth in claim 1, in which said structure is of plastic and is incorporated within the thickness thereof.
